UNITED STATES PATENT OFFICE.

DAVID L. BENDER, OF LEBANON, PENNSYLVANIA.

DEVICE FOR HOLDING AND CARRYING SHOE PARTS.

1,357,439.

Specification of Letters Patent.

Patented Nov. 2, 1920.

Application filed May 22, 1920. Serial No. 383,597.

To all whom it may concern:

Be it known that DAVID L. BENDER, a citizen of the United States, residing at Lebanon, in the county of Lebanon and State of Pennsylvania, has invented certain new and useful Improvements in Devices for Holding and Carrying Shoe Parts, of which the following is a specification, reference being had to the accompanying drawings.

10 This invention relates to devices for holding and carrying shoe parts.

The old method used in shoe factories for holding the various parts of the shoe together before assemblage consists of tying 15 the parts in bundles by means of twine, which is very inconvenient and expensive and there is danger of the twine breaking and the various parts being separated.

It is therefore an object of the invention 20 to provide a device which may be used indefinitely for holding various shoe parts without the danger of the parts becoming separated or lost.

Another object of the invention is to provide 25 a device of this character capable of holding the various forms of shoe parts so that they may be conveyed to the desired place for assemblage.

Another object is to provide a device of 30 this character which is adjustable to accommodate the size of the parts placed on the rack.

With these and other objects in view the invention consists in the improved construction 35 and arrangement of parts to be herein-after described, fully claimed and illustrated in the accompanying drawing, in which:

Figure 1 is a vertical elevation and sectional view of a holding device constructed 40 in accordance with an embodiment of the invention,

Fig. 2 is a transverse sectional view showing the position of the central guide,

Fig. 3 is a fragmentary detail view of the foot formed on each standard,

Fig. 4 is a top plan view of the device used for holding parts having many sides, and

Fig. 5 is a perspective view of the lower portion of the holding member shown in Fig. 4.

Referring to the drawings, 5 designates a base having its longitudinal marginal edges extended back upon the base toward each

other to provide guides 6, the purpose of 55 which will be hereinafter described. A guide 7 is formed at the intermediate portion of the base 5 by striking two wings 8 and 9 from the base, and folding the wing 8 over the wing 9. This permits the base to 60 be constructed from sheet metal.

Standards 10 and 11 are provided, each of said standards being formed preferably of wire, one end portion of each standard being flattened to provide a foot 12, each of 65 said feet being slidable through the guide 7 in spaced parallel relation to each other, the extremities of said feet being upturned to prevent disengagement of same from the guide 7. The major portion of each standard is extended upwardly in right angular relation to 70 the foot thereof, the base of the standard 11 being extended back upon its foot in spaced parallel relation thereto and then upwardly to provide a recess 13 while the standard 10 75 is extended directly upward from its foot. Each standard is bent at intervals longitudinally thereof to provide hooks 14, which incline downwardly, said hooks being disposed in spaced relation to each other. The 80 upper end of the standard 11 is formed into a hook 15 while the upper end of the standard 10 is formed into a loop.

The shoe parts designated as A are disposed between the standards 10 and 11, a 85 flexible member such as a length of twine 16 is secured to the base portion of the standard 10. After a certain number of parts have been placed in position, a portion of the twine 16 is extended upwardly in parallel relation to the standard 10, passed over the bundle of parts and then engaged beneath the adjacent hook of the standard 11. The next bundle of parts is placed on top of the first bundle and the twine extended upwardly in parallel relation to the standard 11, and over the top of the second bundle into engagement with the standard 10 beneath one of the hooks of the standard 10. This operation is continued, until the rack 100 is filled, the twine being alternately engaged with the standards and the hooks at intervals, according to the size of the bundle or the number of different parts supported by the device.

If the parts are three-cornered and are difficult to hold between the standards 10 and 11, a holding member 17 is provided.

This member consists of a length of resilient wire which is bent at its intermediate portion to provide an eye 18, said length diverging from the intermediate portion and then 5 extended in angular relation to the diverging portion to provide arms 19. A foot 20 is formed at the end portion of each of the arms 19, said length of wire being extended from each foot toward each other in converging relation to provide arms 22. The end 10 portions of each of the arms 22 is extended in angular relation to said arms to provide hook members 23, said end portions then being extended in spaced parallel relation to 15 the hook portion to provide pintles 24 and clamps 25. A spring 26 is disposed between the end portions of said arms and is held in position by means of the pintles 24 of each arm. This spring is intended to force the 20 clamps 25 toward each other and also the hooks 23 toward each other so as to firmly fasten the holding member in position. The eye 18 of the holding member 17 is intended to engage the hook 15 of the standard 11, 25 said member being disposed between the standards with the feet 20 in the guides 6 of the base. The end portions of the arms 22 are intended to be disposed in the recess 13 of the standard 11, with the clamps 25 in 30 engagement with the base of the standard 11. The three cornered parts above mentioned are disposed between the standards and the arms 19 of the holding member and are secured in the same manner as the parts 35 previously referred to, that is, with the twine alternately engaging the standards 10 and 11, the holding member 17 preventing the parts from disengaging themselves from the device.

40 This device may be made in various sizes to accommodate the style and form of shoe being manufactured. It eliminates the waste of twine, prevents separation or loss of parts, is inexpensive to manufacture and 45 can be used indefinitely as its parts are very simple. Its construction does not limit its utility to shoe parts. It may also be used for holding mail and constructed in sizes large enough to hold various parts of clothing in clothes' factories, so that its utility 50 is unlimited.

What is claimed is:—

1. A device of the character described comprising a base, adjustable standards extending from said base, a holding member detachably engaged with the base and one of the standards, and a flexible member alternately engaging the standards for holding material between said standards and holding means.

2. A device of the character described comprising a base, adjustable standards mounted on said base, hooks carried by the standards, holding means detachably engaged with the base and one of the stand-

ards, said means being adjustable with said standard and a flexible member alternately engaging said standards at intervals and extending laterally of said holding means.

3. A device of the character described comprising a base, a guide formed on said base, a pair of standards having feet, said feet being slidably disposed in said guide in parallel relation to each other, spaced hooks carried by each standard, and a flexible member adapted to be alternately engaged with the hooks of said standards. 70

4. A device of the character described comprising a base, adjustable standards mounted on said base, hooks carried by said standards, a holding frame having one end thereof engaged with one end of one of the standards, the other end portion of said frame being divided, said divided portion interlocking to provide clamps for engagement with the base portion of said standard, and a spring carried by said interlocking portions for urging said clamps into engagement with the other end of said standard. 80

5. A device of the character described comprising a base, adjustable standards mounted on said base, hooks formed in said standards in spaced relation to each other, a holding member comprising a length of material having an eye at its intermediate portion adapted to engage one of said standards, said length diverging from the eye, the major portions of said length being extended from the ends of the diverging portion in angular relation thereto to provide a plurality of arms, feet formed at the end portions of said arms, the end portions of said length converging from said feet toward and crossing each other, clamps formed on the extremity of said end portions adapted to 100 engage one of said standards, and means carried by said end portions for urging said clamps into engagement with said standard. 95

6. A device of the character described comprising a base, having longitudinal marginal edges extended back toward each other to provide guides, a guide formed at the intermediate portion of said base, a pair of standards, each standard having a foot on one end slidably disposed in the second mentioned guide, each of said standards having hooks formed therein in spaced relation to each other longitudinally of the standard, one of said standards being extended back upon its foot in parallel relation thereto and then upwardly to provide a recess, a hook member formed on the upper end of said standard, a holding member comprising a frame, the intermediate portion of one end of the frame being extended beyond the 115 sides of the frame for engagement with the hook on the end of the last mentioned standard, and means carried by the other end of said frame for engagement with the marginal guides of the base, the portion of the 120

130

last mentioned end of the frame between said feet being disposed in said recess in engagement with said standard, and a flexible member adapted to alternately engage the 5 hooks of the standard between said frame.

7. A device of the character described comprising a base, standards extending from said base, each of said standards consisting of a length of material having spaced loops

formed therein, said loops inclining toward 10 one end of the standard to provide hooks, and a flexible member extending between and alternately engaging the hooks of the standard.

In testimony whereof I hereunto affix my 15 signature.

DAVID L. BENDER.
